US00D892614S

(12) **United States Design Patent** (10) **Patent No.:** **US D892,614 S**
Boeijen et al. (45) **Date of Patent:** **** Aug. 11, 2020**

(54) **CAP FOR CONTAINER**(71) Applicant: **Ecolab USA Inc.**, Saint Paul, MN (US)(72) Inventors: **Paul J. Boeijen**, Bussum (NL); **Diego Fort**, Mönchengladbach (DE)(73) Assignee: **Ecolab USA Inc.**, Saint Paul, MN (US)(**) Term: **15 Years**(21) Appl. No.: **29/673,056**(22) Filed: **Dec. 11, 2018**(30) **Foreign Application Priority Data**

CLAIM

We claim the ornamental design for a cap for container, as shown and described.

DESCRIPTION

FIG. 1 is a top view of our new design for a cap for container shown with the cap in a closed position;
FIG. 2 is a bottom view thereof shown with the cap in the closed position;
FIG. 3 is a front view thereof shown with the cap in the closed position;
FIG. 4 is a left side view thereof shown with the cap in the closed position;
FIG. 5 is a right side view thereof shown with the cap in the closed position;
FIG. 6 is a back view thereof shown with the cap in the closed position;
FIG. 7 is a top perspective view thereof shown with the cap in the closed position; and
FIG. 8 is a bottom perspective view thereof shown with the cap in the closed position;

FIG. 9 is a top view of the cap for container shown with the cap in an open position;
FIG. 10 is a bottom view thereof shown with the cap in the open position;
FIG. 11 is a front view thereof shown with the cap in the open position;
FIG. 12 is a left side view thereof shown with the cap in the open position;
FIG. 13 is a right side view thereof shown with the cap in the open position;
FIG. 14 is a back view thereof shown with the cap in the open position;
FIG. 15 is a front perspective view thereof shown with the cap in the open position; and,
FIG. 16 is a bottom perspective view thereof shown with the cap in the open position.
